UNITED STATES PATENT OFFICE.

GABRIEL J. CASSIDY, OF HASTINGS, MINNESOTA.

SPRAYER NOZZLE.

Application filed June 8, 1920. Serial No. 387,293.

To all whom it may concern:

Be it known that I, GABRIEL JOSEPH CASSIDY, a citizen of the United States, residing at Hastings, in the county of Dakota 5 and State of Minnesota, have invented a new and useful Sprayer Nozzle, of which the following is a specification.

The device forming the subject matter of this invention is a nozzle.

10 The object of the invention is to improve the valve which controls the passage of liquid through the nozzle.

It is within the province of the disclosure to improve generally and to enhance the 15 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the 25 invention shown can be made without departing from the spirit of the invention.

In the accompanying drawings:—

Figure 1 shows in longitudinal section, a nozzle constructed in accordance with the 30 invention; Figure 2 is a plan of the nozzle; Figure 3 is a plan of the valve; Figure 4 is a cross section on the line 4—4 of Figure 1; and Figure 5 is a diagrammatic side elevation, showing the spring strip as the 35 same appears before it is compressed.

The nozzle embodying this invention includes a body 1 having a neck 2. A head 3 is provided which may be of any desired construction.

40 In the body 1 there is formed a bore 20 provided at its forward end with a conical seat 21 communicating with a reduced duct 22 opening into an enlarged passage 23 of less diameter than the bore 20, and provided with a flared mouth 24 discharging into the head 3. A nipple 25 is threaded into the rear end of the bore 20 and is adapted at 26 in any suitable way, to hold a hose (not shown). The body 1 is provided with an elongated slot 27 communicating with the bore 20, there being an opening 28 in the body, to the rear of the slot. A valve 29, in the form of a rod, is mounted for reciprocation in the bore 20 55 and is provided with a point 30 adapted to cooperate with the seat 21. Longitudinal

grooves 31 extend the full length of the valve 29, up to the point 30, the grooves 31 being straight from end to end.

A closure piece 32 is mounted on the body 60 1 and serves to prevent the liquid from finding its way from the bore 20 outwardly through the slot 27. The closure piece 32 is preferably made of fiber or other water proof material and has a slot 33 located to 65 the rear of the slot 27 in the body 1. A spring strip 34 is mounted on the closure piece 32, the spring strip 34 being curved or otherwise formed, to fashion a boss 35 at the forward end of the strip. The 70 spring strip 34 is provided with a slot 36 coinciding with the slot 33 of the closure piece 32. A securing element 37, such as a screw, passes through the slot 36 of the spring strip 34 and through 75 the slot 33 of the closure piece 32, the securing element being mounted in the opening 28 of the body 1. The securing element 37 holds the closure piece 32 and the spring strip 34 on the body 1 for right line reciprocation. A connecting element 38, such as a screw, passes through the spring strip 34 and the closure piece 32 and is mounted at its inner end in the valve 29, the connecting element being located in the slot 27 80 of the body 1. The connecting element 38 connects the valve 29 with the parts 32 and 34 in such a way that when the said parts are reciprocated by means of the boss 35, the points 30 of the valve may be moved 90 toward and away from the seat 21, thereby to regulate the flow of liquid through the nozzle. As shown in Figure 5 of the drawings, the spring strip 34 is originally bowed but is pressed flat by the action of the screw 95 38, the closure piece 32 thus being held down securely on the body 1, to prevent a leakage of liquid through the slot 27 in the body.

Having thus described the invention, what is claimed is:—

1. In a device of the class described, a body provided with a bore, there being a tapered seat at the forward end of the bore; a valve mounted for reciprocation in the 105 bore and adapted to cooperate with the seat, the valve having a longitudinal groove which is closed by the seat when the valve is advanced; and longitudinally sliding means for manipulating the valve from a point 110 external to the body.

2. A nozzle comprising a body having

a bore, there being an elongated slot in the body communicating with the bore; a valve mounted to reciprocate in the bore; a closure on the outer surface of the body and 5 extending across the slot; a bowed spring strip superposed on the closure; a connecting element located in the slot and engaging the valve, the connecting element passing through the closure and engaging the 10 spring strip to put the same under tension; and a securing element connecting the clo-

sure and the spring strip with the body, the closure and the strip being slotted to receive the securing element and to permit a reciprocation of the strip and the closure. 15

In testimony that I claim the foregoing as my own, I have hereto affixed my signature in the presence of two witnesses.

GABRIEL J. CASSIDY.
